[57] CLAIM

The ornamental design for a stairwell vacuum hose, as shown and described.

DESCRIPTION

FIG. 1 is a front, top and side perspective view of the stairwell vacuum hose showing my new design;
FIG. 2 is a front elevational view thereof;
FIG. 3 is a rear elevational view thereof;
FIG. 4 is a side elevational view thereof;
FIG. 5 is an opposite side elevational view thereof; and,
FIG. 6 is a top plan view thereof, the bottom being a mirror image of the top view shown.

FIG. I

FIG. 2

FIG. 3

FIG. 4

FIG. 5

FIG. 6
